AWNNG TYPE WINDOW STRUCTURE

Samuel C. Reynaud, Detroit, Mich.

Application February 26, 1945, Serial No. 579,833

20 Claims. (Cl. 189—67)

1

The present invention relates to metal window structures, and more particularly to an awning type window having vertically sliding and swinging sash members.

The primary object of the invention is to provide a vertically sliding and swinging sash structure for windows and other openings with operating mechanism for raising and lowering the windows with considerable ease.

Another object of the invention is to provide a vertically sliding and swinging sash structure for windows having automatic means controlled by the operating mechanism for locking the sash members in a closed position, to prevent unauthorized persons from opening the windows by grasping the lower portion thereof and exerting a pull force thereon.

Another object of the invention is to provide a window structure of the awning type having vertically sliding and swinging sash members which are adapted to be operated by a slide bar at each side of the window frame through the medium of suitable linkage and to provide means on the slide bar and linkage for initiating swinging movement of the sash members on their pivot points during the first movement applied to the slide bars to thereby break the joint between the linkage and pivot pin and permit the continued movement of the slide bars to swing the windows to an open position.

Another object of the invention is to provide a window structure of the awning type having vertically sliding and swinging sash members which are adapted to be opened and closed by means of operating mechanism at each side of the window structure, including slide bars and linkage arranged so that upon movement of the slide bars in an upward direction to close the windows, means on the linkage will be engaged by cam means on the slide bars to completely close the vertically sliding and swinging sash members and give an added impetus thereto to force the sash members to their completely closed position.

Another object of the invention is to provide an awning type metal window structure, including a series of vertically sliding and swinging sash members which are pivoted at their upper end to the operating slide bars at each side of the window structure in such a manner as to permit a predetermined amount of sliding movement of the slide bars prior to the exertion of a force downward on the pivot point of the sash member so that a projection carried by the slide member and received in a slot in the pivot mem-

2

bers of the vertically swinging sash members will free itself from said slot during the initial downward movement of the operating slide bars to thereby unlock the pivots of the swinging sash members and permit the same to swing freely upon their pivots upon continued downward travel of the slide bars.

Another object of the invention is to provide a metal window construction of the awning type having a series of vertically sliding and swinging sash members having the pivot pins thereof arranged with the slots therein so as to receive the projections carried by the slide bars at each side of the window structure during the closing movement of the window sashes and thereby lock the pivot against turning movement and simultaneously exert a slight closing force on the pivot members, so as to exert an additional closing force on the vertically sliding and swinging sash members, and force the same home upon their seats in the window frame.

Another object of the invention is to provide a metal window structure of the above-mentioned type in which the slide bars may be adjusted to space the projections carried thereby various slight distances apart to permit the adjusting of said slide bars and cause the freeing of said projections from the slots in the pivot pins of the sash members in predetermined timed relation and succession.

Another object of the invention is to provide a metal window structure of the awning type having vertically sliding and swinging sash members controlled by means of operating mechanism at each side of the window, including slide bars and linkage arranged and connected so that certain portions of the slide bar may be disconnected to facilitate the operation of a single window while permitting the remaining windows to be closed.

Another object of the invention is to provide a metal window structure having vertically sliding and swinging sash members which may be opened to facilitate washing the outer surfaces of the windows from the inside of the building so as to eliminate the need of employing ladders and the like for washing the windows on the exterior of the building.

Other objects and advantages of the invention will become apparent during the course of the following description of the accompanying drawings, wherein:

Figure 1 is a front elevational view of a window structure embodying the invention, illustrating portions thereof in section and broken away in

order to disclose the various details of construction;

Figure 2 is a vertical cross-sectional view taken on line 2—2 of Figure 1, illustrating the arrangement of the various operating parts and mechanisms for opening and closing the windows and the arrangement of the pivot points of the linkage and the windows when the sash members are in their closed position;

Figure 3 is a vertical cross-sectional view similar to Figure 2 looking in the same direction and illustrating the window operating mechanism and the vertically sliding and swinging sash members in their partly opened position;

Figure 4 is a horizontal cross-sectional view taken on the irregular line 4—4 of Figure 1 showing the manner in which the projection carried by the slide bar is received in a slotted opening of a pivot pin carried by the upper end of the sash member;

Figure 5 is a vertical cross-sectional view on the projected line 5—5 of Figure 3, illustrating the position of the locking projection relative to the slotted pivot member when the window sash is in its partly opened position;

Figure 6 is a vertical cross-sectional view taken on line 6—6 of Figure 1 looking in the direction of the arrows and showing the manner in which the meeting edges of the sash members are seated against one another to provide a relatively tight joint therebetween;

Figure 7 is a horizontal cross-sectional view taken on line 7—7 of Figure 1 looking in the direction of the arrows and illustrating the cross-sectional shape of the cam surface members carried by the vertically movable slide bar and the window sash connecting linkage;

Figure 8 is a side elevational view of one of the links employed for connecting the sash members and the side portions of the window frame;

Figure 9 is a side elevational view of the connecting link illustrated in Figure 8 showing the manner in which the same is formed to provide cam surfaces thereon;

Figure 10 is a side elevational view of a portion of the vertically movable slide bar showing the manner in which the cam projection is secured thereto for cooperative inter-engagement with the cam surfaces carried by the link members extending between the sash members and window frame structure;

Figure 11 is an edge elevational view of the slide bar shown in Figure 10 illustrating the locking projection at the top thereof for being received in a slot in the pivot pin of said sash members and further showing the shape of one of the cam members carried by the slide bar for cooperative inter-engagement with the cam surfaces on the links connecting the sash members with the window frame;

Figure 12 is a side elevational view of one of the bracket members which is adapted to be attached to the upper edge of each sash member at the sides thereof to provide pivotal connecting means between the sash members and the operating slide bars; and

Figure 13 is a side elevational view of a bracket which is adapted to be adjustably secured to the slide bar to provide a bearing member for receiving the pivot pin of the bracket shown in Figure 12 at the upper edge of each sash member.

Detailed description of the invention

In the drawings, wherein for the purpose of illustrating the invention there is shown a pre-

ferred embodiment of the same, including the operating mechanism for the sash members and the various parts incident thereto, the reference character 5 will generally be employed to designate a window frame formed from Z-bars or the like including side, top and end bars arranged with their ends connected together in rectangular relationship. The window frame bars include a web portion 6 and oppositely extending flange portions 7 and 8 (Figures 4 and 7). The window frame 5 may be installed in a window opening in a building or the like in the usual manner and may be fixed in place by screws, bolts or other fastening means.

15 The window frame 5 is adapted to be provided with a series of vertically sliding and swinging sash members 9 which are rectangular in construction and also may be formed of Z-bars or other cross-sectional shapes and include a web portion 10 having oppositely extending flanges 12 and 13. Glass window panels 14 are installed in the vertically sliding and swinging sash members 9 and are held in place by glazing or packing strips as at 15.

20 Slidably mounted on the web portion 6 of the side window frame bars is a slide bar 16 having elongated slots 17 which are received on studs 18 having their ends riveted in place as at 19 and being formed with relatively large heads 20 to retain the slide bars 16 in position. While there is shown in the drawings a window opening mechanism for only one side of the window structure, it is to be noted that both sides thereof will be provided with the same operating 30 mechanism, and since they are identical in construction and operation, the mechanism of one side only will be described. It is intended to form the slide bars 16 of connected sections 21 adjustably fastened together by means of a screw and slot connection 22 and 23 respectively.

25 Affixed to each of the window sash members 9 at the upper sides thereof is a pivot pin supporting bracket 24 having a pair of spaced longitudinally extending slots 25 for receiving anchoring screws as at 26. The upper end of each pivot pin supporting bracket 24 projects slightly above the top sash frame member and is fitted with a pivot pin 27. A depression 28 is formed in the pivot pin supporting bracket 24 for engaging the web portion 10 of the window sash to facilitate adjustment of the pivot pin 27 and the tightening and loosening of either one of the fastening screws 26 to thereby adjust the pivot pin supporting bracket 24 in its proper position. The pivot pin 27 is secured within an opening in the upper end of the pivot pin supporting bracket by being riveted or spun as at 30 (Figure 5) so as to securely lock the pivot pin to the bracket and maintain the same against rotary displacement.

30 Each of the window sashes 9 is pivotally secured to the web portion 6 of the window frame by means of pivot links 31 which have one of their ends attached to the web portion 10 of the window sash by means of an enlarged headed rivet 32 while the other end of each of the pivot links 31 is pivotally attached to an enlarged headed rivet 33 anchored in an opening 34 in the window frame web portion 6. The pivot pin 33 for each of the pivot links 31 is provided with a guide portion 35 for slidably guiding and additionally retaining the slide operating bars 16 in sliding contact with the web portion 6 of the window frame. The guide portion 35 of each pivot pin 33 operates in an elongated slot 36 formed in the slide bar 16. It will thus be seen

that the sash frame 5 may be swung about the horizontal axis of the pivot pins 32 and 33 by means of the connecting links 31.

In order to move the upper edge of the window sash members downwardly and upwardly, a pivot bracket 37 is attached to the slide bar 16 by means of a pin and slot connection 39 and 40 to permit relative sliding movement between the operating slide bar 16 and the bracket 37, during the upward and downward travel thereof while being guided along the web portions 6 of the window frame 5. The upper end of the pivot bracket 37 is formed with a bearing opening 41 for being received on the pivot pin 27 (Figure 5) so that vertical sliding movement of the operating slide bar 16 will push upwardly on the pivot pin or downwardly to close and open the window sash respectively. Since the pivot pins 32 by which the links 31 are connected to the sash members 10 are located well above the mid-points of the side portions 10 thereof, about two thirds of the weight of the sash member 10 is disposed below the pivot pins 32, thereby overbalancing the sash members 10 at their lower portions. This overbalancing effect tends to normally urge the pivot pins 27 upward, thereby extending upwardly the pivot brackets 37 slidably mounted on the upper ends of the slide bars 16.

It is to be understood that the adjustably connected sections 21 comprising the slide bar 16 may be constructed to accommodate a pair of vertically sliding and swinging sash members in which case a pair of pivot brackets 37 would be affixed to each section 21 of the slide bar with the joint of the lower section 21 being arranged so as not to interfere with the slide openings for supporting the slide bar 16. As shown clearly in Figure 5, the pivot bracket 37 is slightly offset as at 43 and is slotted as at 44 for a purpose which will be presently fully described.

Mounted on the sections 21 of the slide bar 16 at spaced intervals therealong adjacent the pivot pins 27 is a series of key members 45. As shown in Figures 10 and 11, the key members are T-shaped and are provided with reduced portions 47 adapted to be received in square openings in the slide bar sections so as to be riveted therein as at 46. The locking keys 45 are adapted to be received in slightly wider diametrically disposed slots 48 formed in the radial wall of the pivot pins 27 to provide mutually engaging locking and camming members when the slide bar 16 at each side of the window frame is raised to the limit of its uppermost position. It is to be noted in Figure 12 that the slot 48 of the pivot pin 27 is at an angle of approximately 7.5 degrees so that when the locking key is projected into said slot 48, it exerts a camming action against the slightly inclined walls thereof so that the pivot pin 27 will be given a slight movement in a lateral direction to close the sash upon upward sliding movement of the slide bar 16 when closing the window sashes.

When the slide bar 16 is drawn downwardly as shown in Figure 5, the locking key 45 moves downwardly out of the slot 48 in the pivot pin 27 and is received in a slot 44 of the pivot bracket 37 and limited against further movement by said slot 44 as well as the pin and slot connection 39 and 40. Thus, the mutually engaging locking and camming surfaces are disengaged and the window sash 9 will be free to swing outwardly as the upper edge thereof is drawn downwardly by the slide bar at each side of the window frame. Upon the up-travel or stroke of the slide bar 16 at

each side of the window frame, the upper portion of the locking key 45 engages the peripheral edge of the pivot pin 27 and pushes it upward while the sash 9 swings the pivot 27 until the slot 48 therein is in registry with the locking key 45 so as to permit said locking key to enter the slot and exert a camming movement thereto in a lateral direction so as to exert a final closing force on the sash. This mechanism assists a cam device described below in locking the window sash in its closed position when the locking key 45 is received in the slot 48 so as to prevent the same being opened by an unauthorized person grasping the lower edge thereof and exerting a pull force thereon. The pivot bracket 37 is prevented from lateral displacement when the locking key 45 is received in the slot 48 which provides a two-point connection between the slide bar 16 and the bracket. Similarly, the bracket 37 is prevented from lateral movement relative to the slide bar and the pivot pin 39 when the locking key 45 is in the position shown in Figure 5 or displaced from the slot 48 by reason of the fact that the key 45 is received in the slot 44 in the offset portion 43 of the bracket.

Each of the pivot links 31 is formed of a pair of sections 50 and 51 which have their inner ends overlapped and welded or otherwise secured together (Figures 8 and 9) and one edge of the section 51 is beveled and undercut as at 52 to provide a cam surface to initiate swinging movement of the sash members 9 during the initial travel of the slide bar 16 to open the window. Welded to the section 50 of each sash frame pivot link 31 is a cam plate 53 having a beveled surface 54 which is undercut and extends parallel with the beveled undercut surface 52 formed on the upper edge of the section 51. The cam surfaces 52 and 54 are adapted to interlockingly cooperate with a cam plate 56 disposed obliquely on the operating bar 16 in such a manner as to exert an outward force on the pivot links 31 during the initial opening movement of the slide bars 16 to thereby break the joint between the pivot points 27, 32 and 33. The cam plate 56 is provided with beveled undercut cam surfaces 57 and 58 so as to interlock with the cam surfaces 52 and 54 and lock the sash members 9 to prevent them from being opened by an unauthorized person grasping the lower edge thereof and prevent lateral displacement during the initial opening or closing movement of the slide bar 16 and sash members 9. It is to be understood that each pivot link 31 for the respective sash members will be provided with obliquely disposed cam surfaces 52 and 54. Obliquely disposed cam plates 56 may be arranged on the various sections 21 of the slide bars 16 at each side of the window frame in spaced apart relation so as to initiate the opening movement of the window sashes during downward travel of the slide bar 16 and force the window sashes to their seated position against the window frame during upward travel of the slide bar 16 thereby effecting the main locking action on the sashes 9.

Suitable means will be provided for raising and lowering the slide bars 16 and said means may include a horizontal shaft at the lower end of the window frame having crank arms at the ends for connection with the slide bars 16 and a suitable crank operator drivingly connected to the shaft through the medium of suitable gearing, none of which is shown as it forms no part of the present invention. The operating mechanism, including the gearing, will hold or lock the

slide bars 16 against movement so that the series of window sashes may be held in various positions of adjustment. Also, a lower normal type sash member may be employed as an operator for the sash members thereabove with the lower sash member connected and arranged to operate the upper sash members in tandem when the lower normal sash is operated manually.

Operation of the invention

In the position of the relative parts shown in Figure 1, the window sash 9 is in a fully closed position and is locked against unauthorized opening by means of the interengaging cam surfaces 52, 54, 58 and 57 respectively. In this position, the slide bars 16 are in their fully raised position and the window sash 9 is completely closed relative to the frame 5.

Should it be desired to open the window sashes 5, the slide bars at each side of the window frame may be moved downward in a vertical direction by manipulation of the above-mentioned manual operating mechanism (not shown) so that said slide bars will move relative to the sash members a slight amount during their initial movement so that the key members 45 will move out of said diametrically arranged slots 48. The downward movement of the key members as above described to cause displacement of said key members 45 from said slots 48 will exert an outward camming movement on the pivot pins 27 to move them in a direction outward away from the window frame 5 so that the upper end of said sash members will be freed from the window frame. After the key members 45 have been disengaged from the slots 48 in the pivot pins 27, the cam surfaces 52 and 58 will cooperate to exert an outward movement on the pivot links 31 and cause the same to swing about their fixed pivotal points 33. This outward movement breaks the joint between the links 31 and sash member by urging the free swinging ends of the links 31 outward away from the window frame. In so doing, the window sash members are given a rotational movement about their pivot pins 27 and from the initial movement of the slide bars 16, the key projections 45 will have been disengaged from the slots 48 of the pivot pins 27 and the connecting pin 39 of the bracket 37 will have reached the limit of its movement in the slot 40.

Continued downward movement of the slide bars 16 exerts a direct downward pull force on the pivot pins 27 and causes the upper ends of the sash members to be likewise drawn downwardly and thereby rock the sash members on the pivotal connections between the pivot links and sash members. The cam surfaces 52 and 58 will cooperate to exert an opening and outward movement on the pivot links and sash members until they have become disengaged as shown in Figure 2, whereupon further continued movement of the slide bars 16 will swing the sash members to an open position until they reach a horizontal position.

When it is desired to close the window sashes 9, an upward force is exerted on the slide bars 16 at each side of the window frame so as to force the upper end of the window sashes in a vertical direction and permit the sashes to hinge in a direction of closing about the pivot points 32 and 33 of the link members 31. After the window sashes have been swung on their horizontal pivots and raised vertically to a position shown in Figure 3, by means of the slide bars at each side of the window frame, the key projections 45 on

the slide bars will engage the peripheral surface of the pivot pins 27 and force the same upwardly so that the interengaging cam surfaces 54 and 57 will coat and engage to exert an inward pull on the window sashes 9. After the window sashes have thus been operated by the slide bars 16 to a position in which they are almost closed, the key projections 45 will register with the slots 48 in the pivot pins 27 and permit an additional movement of the slide bars 16 relative to the window sashes 9 to thereby permit interlocking of the key members 45 in the slots 48. As this occurs, the pivot pins 27 are given a slight inward movement in the direction of the window frame by reason of the angularity of the slot 48 so as to exert a closing pressure on the window sashes 9 to assist in locking the same in their closed position. Simultaneously, the additional movement and locking action of the slide bars in an upward direction will cause further relative movement between the cam surfaces 54 and 57 and exert an additional closing movement on the window sashes 9 as the key projections 45 become seated or enter the slots 48. It is also to be borne in mind that the pivot pin slots 48 are slightly angled so as to produce said inward and outward slight movement of the pivot pins and sash members in both directions of slide bar movement and when the key projections 45 are moved into and out of said slots 48.

In the event a normal type sash member is employed for opening other sash members, it may be released by mechanical means so that it may be opened and closed independently of the remaining sash members.

It will thus be seen that the operating mechanism above described provides a window structure wherein all of the operative parts are concealed and that the appearance and beauty thereof is enhanced when the window sash members are in their closed or open position.

It is to be understood that the form of the invention herewith shown and described is to be taken as a preferred embodiment of the same and that various changes may be made in the shape, size and arrangement of parts without departing from the spirit of the invention or the scope of the subjoined claims.

What I claim is:

50. 1. A window structure, comprising a window frame having an opening, a sash frame having a panel for closing said opening, link means pivotally connecting said sash frame and window frame, a sliding operating member supported by the window frame having a pivotal connection with one end of said sash frame, and mutually engaging cam surfaces connected respectively to said link means and sliding operating member and operative to lock said sash frame in a closed position in response to the motion of the sliding member toward the end of its travel in a direction to move said sash member to its closed position.
55. 2. A window structure, comprising a window frame having an opening, a sash frame having a panel for closing said opening, link means pivotally connecting said sash frame and window frame, a sliding operating member supported by the window frame having a pivotal connection with one end of said sash frame, and mutually engaging locking surfaces for locking said sash frame in a closed position upon operation of the sliding member in a direction to move said sash member to its closed position, said mutually engaging locking surfaces being carried by the sliding operating member and the pivotal connection

between the end of the window sash and said operating member.

3. A window structure, comprising a window frame having an opening, a sash frame having a panel for closing said opening, link means pivotally connecting said sash frame and window frame, a sliding operating member supported by the window frame having a pivotal connection with one end of said sash frame, and mutually engaging locking surfaces for locking said sash frame in a closed position upon operation of the sliding member in a direction to move said sash member to its closed position, said mutually engaging surfaces being carried by the link means and sliding operating member and operable to exert a slight rotational force to the pivotal connection between the window sash and operating slide.

4. A window operating mechanism for a window structure having a supporting frame and sash member, link means pivotally connecting said sash and frame members, a sliding operating member pivotally connected to the sash member, cam means on the link means and sliding operating member for exerting a push and pull force on said sash member when the same is opened and closed respectively, and interengageable cam means connected respectively to said link means and sliding operating member for locking said sash in a closed position.

5. A window operating mechanism for a window structure having a supporting frame and sash member, link means pivotally connecting said sash and frame members, a sliding operating member pivotally connected to the sash member, cam means on the link means and sliding operating member for exerting a push and pull force on said sash member when the same is opened and closed respectively, and interengageable cam means connected respectively to said link means and sliding operating member for locking said sash in a closed position, said last-named means including mutually engaging surfaces movable relative to one another and controlled by the movement of the operating sliding member.

6. In a window structure having a window frame and a sash frame arranged for vertical sliding and swinging movement, link means at each side of said frame connecting the sash frame to the window frame, a vertically movable operating member pivotally connected to the upper end of said sash frame, and means on the link means for exerting an outward and inward pressure on the sash frame to swing the same about its pivotal connection when the operating member is moved downwardly and upwardly respectively.

7. In a window structure having a window frame and a sash frame arranged for vertical sliding and swinging movement, link means at each side of said frame connecting the sash frame to the window frame, a vertically movable operating member pivotally connected to the upper end of said sash frame, and means on the link means for exerting an outward and inward pressure on the sash frame to swing the same about its pivotal connection when the operating member is moved downwardly and upwardly respectively, said last-named means including interengageable cam surfaces on the link means and operating member respectively.

8. In a window structure having a window frame and a sash frame arranged for vertical sliding and swinging movement, link means at each side of said frame connecting the sash frame to the window frame, a vertically movable operating member having a pivotal connection to the

upper end of said sash frame, means on said pivotal connection for urging said sash frame outwardly and inwardly relatively to said window frame in response to the movement of said operating member downwardly and upwardly respectively, and interengaging cam means on the link means and operating member responsive to the upward movement of said operating member to exert an outward movement on said sash frame.

9. In a window structure having a window frame and a sash frame arranged for vertical sliding and swinging movement, link means at each side of said frame connecting the sash frame to the window frame, a vertically movable operating member having a pivotal connection to the upper end of said sash frame, means on said pivotal connection for urging said sash frame outwardly and inwardly relatively to said window frame in response to the movement of said operating member downwardly and upwardly respectively, and interengaging cooperative cam means on the link means and operating member responsive to the downward movement of said operating member to exert an inward movement of the window sash.

10. In a window structure having a window frame and a sash frame arranged for vertical sliding and swinging movement, link means at each side of said frame connecting the sash frame to the window frame, a vertically movable operating member pivotally connected to the upper end of said sash frame, means on the link means for exerting an outward and inward pressure on the sash frame to swing the same about its pivotal connection when the operating member is moved downwardly and upwardly respectively, and mutually engaging cam means disposed between the pivotal connection of said sash frame and operating member respectively and responsive to the movement of the operating member in one direction for urging the upper end of the sash frame inwardly toward the window frame and responsive to movement of the operating member in a reverse direction for urging the upper end of the sash frame outwardly away from the window frame.

11. A window raising and lowering mechanism for window openings having a frame and movable sash member, comprising link means for pivotally connecting said sash member to said frame, slide bars movably carried by the side portions of said frame, pivot pins projecting from the sides of said sash member, means for slidably connecting said pivot pins to said slide bars and responsive to the movement of said slide bars to swing said sash member relatively to said frame, and mutually engaging cam surfaces on said pivot pins and slide bars for urging said sash member into a closed position relatively to said sash frame in response to the upward movement of said slide bars.

12. A window raising and lowering mechanism for window openings having a frame and movable sash member, comprising link means for pivotally connecting said sash member to said frame, slide bars movably carried by the side portions of said frame, pivot pins projecting from the sides of said sash member, means for slidably connecting said pivot pins to said slide bars and responsive to the movement of said slide bars to swing said sash member relatively to said frame, and mutually engaging cam surfaces in the slide bars and link means for exerting a clos-

ing pressure on said sash member in response to the upward movement of the slide bar.

13. A window raising and lowering mechanism for window openings having a frame and movable sash member, comprising link means for pivotally connecting said sash member to said frame, slide bars movably carried by the side portions of said frame, pivot pins projecting from the sides of said sash member, means for slidably connecting said pivot pins to said slide bars and responsive to the movement of said slide bars to swing said sash member relatively to said frame, and mutually engaging cam surfaces disposed between said link means and slide bars for breaking the pivotal joints of said link means and sash member in response to the initial opening of said sash members by said slide bars.

14. A window raising and lowering mechanism for window openings having a frame and movable sash member, comprising link means for pivotally connecting said sash member to said frame, slide bars movably carried by the side portions of said frame, pivot pins projecting from the sides of said sash member, means for slidably connecting said pivot pins to said slide bars and responsive to the movement of said slide bars relative to said frame, mutually engaging cam surfaces on said pivot pins and slide bars for urging said sash member into a closed position relatively to said sash frame in response to the upward movement of said slide bars, and cam surfaces carried by said link means and slide bars interengagingly cooperable for initiating opening movement of the sash member in response to the movement of the slide bars in one direction and for exerting a closing movement on said sash member in response to the movement of said slide bars in the opposite direction.

15. A window raising and lowering mechanism for window openings having a frame and movable sash member, comprising link means for pivotally connecting said sash member to said frame, slide bars movably carried by the side portions of said frame, pivot pins projecting from the sides of said sash member, means for slidably connecting said pivot pins to said slide bars and responsive to the movement of said slide bars to swing said sash member relatively to said frame, mutually engaging cam surfaces on said pivot pins and slide bars for urging said sash member into a closed position relatively to said sash frame in response to the upward movement of said slide bars, and interlocking cooperative cam means on the link means and slide bars for exerting a final closing movement on the sash member in response to the final upward movement of said slide bars.

16. A window structure, comprising a window frame, a series of sash members, link members pivotally connected to each side of the window frame arranged with their outer ends pivoted to the sash members, slide bars arranged at each side of the window frame, pivot pins projecting from the side edges of said sash members, bracket means slidably carried by the slide bars having openings for receiving said pivot pins, and mutually engaging key and slot means on the slide bars and pivot pins movable into and out of engagement in response to window opening and closing sliding movement of the slide bars and responsive to the final closing movement of said slide bars to exert a closing force on the pivot pins and sash members relatively to said window frame.

17. A window structure, comprising a window frame, a series of sash members, link members

pivotedly connected to each side of the window frame arranged with their outer ends pivoted to the sash members, slide bars arranged at each side of the window frame, pivot pins projecting from the side edges of said sash members, bracket means slidably carried by the slide bars having openings for receiving said pivot pins, and mutually engaging key and slot means on the slide bars and pivot pins movable into and out of engagement in response to window opening and closing sliding movement of the slide bars and responsive to the final closing movement of said slide bars to exert a closing force on the pivot pins and sash members, said slot means being slightly angled with respect to the key means whereby to effect a cam action and exert said closing force on the pivot pins and sash members.

18. A window structure, comprising a window frame, a series of sash members, link members pivotally connected to each side of the window frame arranged with their outer ends pivoted to the sash members, slide bars arranged at each side of the window frame, pivot pins projecting from the side edges of said sash members, bracket means slidably carried by the slide bars having openings for receiving said pivot pins, mutually engaging key and slot means on the slide bars and pivot pins movable into and out of engagement in response to window opening and closing sliding movement of the slide bars and responsive to the final closing movement of said slide bars to exert a closing force on the pivot pins and sash members relatively to said window frame, and interengaging cam surfaces on the link members and slide bars responsive to the movement of said slide bars in opposite directions to exert an opening and closing movement on said sash members.

19. A window structure, comprising a window frame, a series of sash members, link members pivotally connected to each side of the window frame arranged with their outer ends pivoted to the sash members, slide bars arranged at each side of the window members, pivot pins projecting from the side edges of said sash frames, bracket means slidably carried by the slide bars having openings for receiving said pivot pins, mutually engaging key and slot means on the slide bars and pivot pins movable into and out of engagement in response to window opening and closing sliding movement of the slide bars and responsive to the final closing movement of said slide bars to exert a closing force on the pivot pins and sash members relatively to said window frame, and interengaging cam surfaces on the link members and slide bars responsive to the movement of said slide bars in opposite directions to exert an opening and closing movement on said sash members, said cam surfaces being inclined relatively to said link members and slide bars respectively whereby to lock the sash member in its fully closed position when the slide bars are moved to the limit of their travel in one of said directions of movement.

20. A window structure, comprising a window frame, a series of sash members, link members pivotally connected to each side of the window frame arranged with their outer ends pivoted to the sash members, slide bars arranged at each side of the window frame, pivot pins projecting from the side edges of said sash members, bracket means slidably carried by the slide bars having openings for receiving said pivot pins, and mutually engaging key and slot means on the slide

bars and pivot pins movable into and out of engagement in response to window opening and closing sliding movement of the slide bars and responsive to the final closing movement of said slide bars to exert a closing force on the pivot pins and sash members relatively to said window frame, said slide bars and link members being provided with interengaging cooperative cam surfaces for initiating opening movement of said sash members in response to the movement of the slide bars in one direction and for locking said sash members to said window frame in response to the movement of the slide bars in the opposite direction.
